UNITED STATES PATENT OFFICE.

WILLIAM J. LONG AND JAMES B. NOLDER, OF WINDBER, PENNSYLVANIA.

ELECTRIC RAIL-BOND.

SPECIFICATION forming part of Letters Patent No. 700,346, dated May 20, 1902.

Application filed February 25, 1902. Serial No. 95,539. (No model.)

To all whom it may concern:

Be it known that we, WILLIAM J. LONG and JAMES B. NOLDER, citizens of the United States, residing at Windber, in the county of Somerset and State of Pennsylvania, have invented a new and useful Electric Rail-Bond; and we do hereby declare the following to be a full, clear, and exact description of the invention, such as will enable others skilled in the art to which it appertains to make and use the same.

The invention relates to an electric rail-bond.

Heretofore great difficulty has been experienced in electric rail-bonds for mine-railways, where the rails are small and where they are often submerged in sulfur-water, and with those forms of electric rail-bonds now in use under such conditions it has been found necessary to employ a man constantly for repairing such electrical connections, especially as the wreckage of a car is exceedingly liable to destroy the bond.

This invention has for its object to provide an electric rail-bond of this character which will be exceedingly inexpensive in construction and which will provide the necessary contact-surface and at the same time be unaffected by the action of the sulfur-water and rust of the rails and fish-plates.

A further object of the invention is to provide an electric rail-bond in which the amount of metal employed will be reduced to a minimum and which will form with the fish-plates and the rails a solid and compact structure that will effectually prevent any injury to the bond in the event of the wreckage of a mine-car.

Also the invention has for its object to produce an electric bond adapted to be applied in position with a minimum amount of labor and capable of lasting as long as the rails and fish-plates without losing its effectiveness.

The invention consists in the novel construction and arrangement of parts hereinafter illustrated and described, and particularly pointed out in the appended claims.

In the drawings forming part of this specification, and in which like numerals of reference designate corresponding parts, Figure 1 is a vertical sectional view of a rail-joint provided with an electric rail-bond construct-

ed in accordance with this invention. Fig. 2 is a horizontal sectional view of the same. Fig. 3 is a detail view of the electric rail-bond. Fig. 4 is a similar view of one of the fish-plates.

Referring to the drawings, 1 designates an electric rail-bond designed for use in mine-railways where the rails 2 are small and where the same are to a great extent submerged in sulfur-water, and the said electric rail-bond consists of a thin copper plate, arranged at one side of the rails 2 and interposed between the web of the rails and one of the fish-plates 3 and 4. The rails are provided at their ends with perforations 5 and 6 for the reception of bolts 7, which extend through the rails and the fish-plates, and the latter are provided with elongated openings 8 and 9, which register with the perforations of the rails and which are elongated to permit the necessary contraction and expansion of the parts.

The electric bond is provided at its ends with elongated openings 10, which register with the inner openings 8 of the fish-plate and with the end perforations of the rails. The bolts are provided at their threaded ends with nuts of the ordinary construction, and suitable locking-washers are designed to be interposed between the nuts and the adjacent fish-plates; but any other form of nut-lock may be employed to prevent the nuts from accidentally unscrewing.

The fish-plate 3 is provided at its inner face with a thin narrow groove 11, conforming to the configuration of the electric-railway bond and forming a seat for the same, the electric rail-bond fitting solidly against the adjacent faces of the webs of the rails and the vertical wall of the groove and the fish-plate 3 forming a housing or casing for the electric rail-bond, whereby the latter is effectually protected from the sulfur-water. Also, by arranging the electric rail-bond between the fish-plate 3 and the rails it is securely protected from vibrations and jars incident to the passage of loaded cars over the rail-joint, and it cannot be broken or otherwise injured through the wreckage of a mine-car.

The electric rail-bond which carries the return-current in an electric-railway system presents a maximum amount of contact-sur-

face and affords an efficient electrical connection and at the same time reduces the amount of material to the minimum. Also it effects a great saving of labor, both in the application of it to the rails and obviating the necessity of employing a workman for looking after the electrical connection between the rails and repairing the same. After the electric rail-bond has been placed in position it cannot be broken off or otherwise rendered ineffective, and it has been found by experience that it will not be affected by sulfur-watter when the rail-joint is submerged in the same, and it will remain effective as long as the rails and the fish-plates last. Furthermore, the electric rail-bond may be manufactured at a greatly-reduced cost, both on account of its simplicity of construction and the small amount of metal involved in its manufacture, and its strength and durability are greatly increased by the manner in which it is supported by the fish-plates and the rails, which prevent any independent jar or vibration of the electric rail-bond. It has also been found by experience that rust of the rails or any corrosion of the copper will not impair the effect of the electrical connection when the electric rail-bond is arranged as set forth herein.

Having thus fully described our invention, what we claim as new, and desire to secure by Letters Patent, is—

1. In a device of the class described the combination with rails, of a fish-plate provided at its inner face with a longitudinal groove, an electric rail-bond consisting of a thin copper

plate seated in the groove and entirely filling the same throughout its entire length and interposed between the rails and the fish-plate, said fish-plate forming a casing or housing for the electric rail-bond and supporting the same at the upper and lower edges thereof throughout the entire length of the same, substantially as described.

2. In a device of the class described, the combination of the rails provided at their ends with perforations arranged in pairs, fish-plates arranged at opposite sides of the rails and provided with elongated openings arranged in pairs, an electric rail-bond consisting of a thin copper plate provided at its ends with elongated openings registering with the end perforations of the rails and with the inner openings of the fish-plates, said electric rail-bond being snugly seated and concealed within a groove of the inner face of one of the fish-plates and entirely filling the same throughout its entire length, whereby it forms a solid structure with the rails and fish-plates and is supported and protected by the same, and fastening devices, passing through the said perforations and openings, substantially as described.

In testimony whereof we have hereto affixed our signatures in the presence of two witnesses.

WILLIAM J. LONG.
JAMES B. NOLDER.
